DETAIL FOR AWNING OR JALOUSIE TYPE WINDOWS

Robert H. Brunzie, Chicago, and Frederick M. Fink, Glenview, Ill., assignors to Continental Aluminum Products Company, Chicago, Ill., a corporation of Delaware

Filed Aug. 1, 1960, Ser. No. 46,459
5 Claims. (Cl. 20—53)

This invention relates to awning or jalousie type windows, and has particular reference to an improved assembly and operator therefor.

One of the principal objects of the invention is to provide an improved operator and assembly which seals out the light ordinarily seen between the frame jamb and the baffle of an awning type window.

Another object is to provide a construction for a vent or awning type window which will prevent rays of light from entering between the vent baffle and the frame jamb.

Still another object is to provide an assembly for an awning or jalousie type window characterized by the elimination of threaded fastenings for securing the vent head and baffle together.

A yet further object comprehends a construction for the louvers of a jalousie type window whereby the vent head and baffle can be so constructed that the parts are assembled with snap fitting extrusions making unnecessary the use of threaded fastening devices.

Other objects and important features of the invention will become apparent from a study of the specification following taken with the drawings, which together describe and illustrate a preferred embodiment of the invention, and what is now considered to be the best mode of practicing the principles thereof. Other embodiments may be suggested to those having the benefit of the teachings herein, and such other embodiments are intended to be reserved especially as they fall within the scope and spirit of the subjoined claims.

In the drawings:

FIG. 1 is a front elevational view of a detail of an awning or jalousie type window, said window having the improvements according to the present invention embodied therein;

FIG. 2 is an end view looking in the direction of the arrows 2—2 seen in FIG. 1;

FIG. 3 is a rear elevational view of FIG. 1, certain parts being broken away, and certain other parts being shown in section to show details thereof;

FIG. 4 is a detail of the other end of the window seen in FIG. 1, certain parts being shown in broken away section to illustrate details thereof;

FIG. 5 is a section taken along the line 5—5 of FIG. 3 looking in the direction of the arrows;

FIG. 6 is a detailed sectional view taken along the line 6—6 of FIG. 3, looking in the direction of the arrows; and

FIG. 7 is a detailed section looking in the direction of the arrows 7—7 of FIG. 3.

Referring now to the drawings, the improved awning type window according to the present invention is referred to generally by the reference numeral 10, and includes a pair of spaced frame jambs 11, see FIG. 1, and 12, see FIG. 4. The two frame jambs 11 and 12 are joined by a frame head 13, see also FIG. 5, the frame head 13 being formed from an extrusion of soft metal, preferably aluminum, and having semi-hollow screw bosses 14 and 16 in a web 17 thereof, bosses 14 and 16 being adapted to receive self-tapping screws 18 and 19 which hold the frame jambs 11 and 12 to the frame head 13.

For purposes of description in this specification, a frame head will be referred to, but as is conventional in

2

all types of sash, the jambs 11 and 12, may be joined at other points throughout their length by rails, not shown, which serve essentially the same function as the frame head 13. The frame jambs 11 and 12 have a flange 15 and frame head 13 has a flange 15A all lying in a common plane and adapted to fit against a window opening, not shown.

A vent sash indicated generally by the reference numeral 20 is adapted to pivot within the space defined by the spaced frame jambs 11 and 12 and the frame head

10 13. The sash 20 includes a vent jamb 21, see FIG. 4, and a vent jamb 22 spaced therefrom, see FIG. 3. The two spaced jambs 21 and 22 are joined along the top thereof by a vent head 23, see FIGS. 3 and 4. The two vent jambs 21 and 22 are essentially T-shaped in cross section and include a front flange 24, see also FIGS. 1 and 4, and a leg 26, see FIG. 5. A smaller flange 27 extends from the leg 26 and is spaced from the front flange 24, the two flanges 24 and 27 providing a space to receive a pane of window glass, not shown.

15 20 Likewise, as seen in FIGS. 5 and 6, the vent head 23 has a front flange 28 lying in the same plane as the flange 24 of the vent jambs 21 and 22, and the vent head 23 has a web 29 with a back flange 31 extending therefrom. The plane of the back flange 31 is co-extensive with the back edge of the web 26 of the vent jambs 21 and 22, as seen particularly in FIGS. 5 and 6, and the flange 26 of the vent jambs 21 and 22 is notched as at 32 to receive the flange 31 of the vent head 23.

25 30 A smaller flange 33 extends from a semi-hollow screw boss 34 also extending from the web 29 of the vent head 23. The flange 33 is coplanar with the flange 27 of the vent jambs 21 and 22, the flanges 33 and 27 being adapted to hold a pane of glass therein. The groove defined by the aforesaid flanges is generally provided with 35 suitable gasket material such as vinyl compound or the like, for holding the pane of glass in position.

35 40 The vent head 23 is secured to the vent jambs 21 and 22 by means of self-tapping screws 36 tapped into the screw bosses 34.

45 40 A seal is provided for the top of the sash 20 thus far described, and such seal includes a drip cap 37 extending from the frame head 13, drip cap 37 having a groove 38 therein to receive weather stripping 39 bearing against a baffle 41, see particularly FIGS. 5 and 6. Baffle 41 has a flange 42 adapted to move against the weather stripping 39 when the sash 20 is in the closed position as seen in FIG. 5.

50 45 Structure is provided for holding the baffle 41 to the vent head 23, and to this end the flange 31 of the vent head 23 has a land 43 extending lengthwise thereof, land 43 being in snapping engagement with a snap groove 44 extending from a flange 46 of the baffle 41. The flange 46 lies in a plane co-extensive with the plane of the flange 31, as seen in FIG. 6. The baffle 42 has a flange 47 on the front thereof, the plane of which is co-extensive with the plane of the flange 28 of the vent head 23. The flange 47 terminates in a grooved flange 48, which is in snapping engagement with a land 49 on the vent head 23.

55 50 Since the vent head 23 and the baffle 41 are made of a yieldable material having a certain amount of resiliency, such as aluminum, the baffle 41 and the vent head 23 are thus readily adapted to be assembled without the need of self-tapping screws which have heretofore been necessary.

60 55 Structure is provided for pivoting the sash 20 in the space or opening defined by the spaced frame jambs 11 and 12 and the frame head 13, and to this end a sash operator 51 has a pair of bosses 52 and 53 which extend into complementary openings in the web 26 of the vent jambs 21 and 22. The operator is held in position against

the web 26 by means of screws 54 and 56 tapped into the operator 51 and extending through respective openings 57 and 58 in the web 26, see also FIG. 4.

The operator 51 has a boss 59 extending through an opening 61 in a web 62 of the frame jambs 11 and 12, see FIGS. 2 and 3. The boss 61 is provided with a nylon bushing 63 to give a smooth friction free operation in swiveling or pivoting the sash 20. An E-ring 64 fits on a groove in the boss 61 to hold the assembly together.

In the construction of windows of the general type as disclosed herein, the baffle 41 is constructed of a length so as to abut the web 61 of the frame jambs 11 and 12, but the manufacturing tolerances in devices of this type is such that a very close sliding fitting between the end of baffle 41 and the web 62 is not desirable in the event of warping of the opening in which the window 10 is positioned, and also because such close tolerances would tend to cause the sash 20 to bind. Accordingly, the ordinary manufacturing tolerances are such that a slight gap is present between the end of the baffle 41 and the web 62 of the frame jambs 11 and 12. This gap permits stray light to be seen from the interior of the structure in which the window 10 is positioned, a very undesirable feature. According to the present invention, the stray light which would come between the end of the baffle 41 and the proximate frame jamb and between the vent head and its proximate frame jamb is blocked by providing a fillet 66 on the operator 51, the fillet 66 seen in FIGS. 3 and 4 occupying the space between the web 26 of the vent jamb 24 and the web 62 of the frame jambs 11 and 12. Likewise, the fillet 66 has an extension 67 therefrom which fills in the space between the end of the web 31 of the vent head 23, and the web 62, as seen more particularly in FIGS. 3 and 4.

As seen in FIGS. 1 and 4, the web 62 of the frame jambs 11 and 12 is provided with a groove 67 positioning a length of weather strip 68 therein. The width of the weather strip 68 is designed so as effectively to close any gap between the end of the baffle 41 and the web 62. However, without the provision of the fillet 66 and 67 on the operator 51, such blocking of stray light is not ordinarily completely effective.

As seen in FIG. 7, the fillet 66 has a land 69 thereon which cooperates with the snap groove 44 of the baffle 41 to assist in holding the baffle 41 in place on the operator 51 and additionally to prevent the entrance of stray light through the joint between the end of the baffle 41 and the web 62 of the frame jamb 12.

The operator 51 has a boss 71 thereon which is connected to means, not shown, in turn connected to operators for other sash 20. As is conventional in windows of this kind, the operators 51 are operated as a unit by a crank, not shown, at the bottom of each window unit.

While the invention has been described in terms of a preferred embodiment thereof, its scope is not intended to be limited to the precise embodiment herein shown, nor otherwise, than by the scope of the appended claims.

We claim:

1. In an awning type window, a pair of spaced frame jambs and a frame head extending between said jambs including means for securing said jambs to said frame head, a vent sash adapted to pivot within the space defined by said spaced frame jambs to open and closed position, said sash comprising a pair of vent jambs and a vent head connected at each end thereof to said vent jambs, said vent jamb including a flange extending therefrom adapted to overlie and close against a frame jamb, a baffle secured to said vent head and having an end thereof extending substantially to the inner face of its proximate frame jamb, an operator secured to one of said vent jambs for moving the vent sash to open and closed positions including means on said operator for providing a pivotal connection to said frame jamb, and a baffle on said operator against stray light passing between the end of the first named baffle and its proximate frame jamb and be-

tween the end of said vent head and the proximate frame jamb.

2. In an awning type window, a pair of spaced frame jambs, a frame head extending between said jambs including means for securing said jambs to said frame head, a vent sash adapted to pivot within the space defined by said spaced frame jambs and thereon to open and closed position, said sash comprising a pair of vent jambs and a vent head connected at each end thereof to said vent jambs, said vent jambs including a flange extending therefrom adapted to overlie and close against a frame jamb, a baffle secured to said vent head and having an end thereof extending substantially to the inner face of its proximate frame jamb, an operator secured to one of said vent jambs for moving the vent sash to open and closed positions including means on said operator for providing a pivotal connection to said frame jamb, and means on said operator preventing stray light from passing between the end of the first named baffle and its proximate frame jamb, and between the end of said vent head and the proximate frame jamb.

3. In an awning type window, a pair of spaced frame jambs, a frame head extending between said jambs including means for securing said jambs to said frame head, a vent sash adapted to pivot within the space defined by said spaced frame jambs and thereon to open and closed position, said sash comprising a pair of vent jambs and a vent head connected at each end thereof to said vent jambs, said vent jamb including a flange extending therefrom adapted to overlie and close against a frame jamb, a baffle secured to said vent head and having an end thereof extending substantially to the inner face of its proximate frame jamb, means for securing said baffle to said vent head comprising complementary grooves and lands on said baffle and said vent head in snapping engagement, an operator secured to one of said vent jambs for moving the vent sash to open and closed positions including means on said operator for providing a pivotal connection to said frame jamb, and a baffle on said operator against stray light passing between the end of the first named baffle and its proximate frame jamb and between the end of said vent head and the proximate frame jamb.

4. In an awning type window, a pair of spaced frame jambs, a frame head extending between said jambs including means for securing said jambs to said frame head, a vent sash adapted to pivot within the space defined by said spaced frame jambs and thereon to open and closed position, said sash comprising a pair of vent jambs and a vent head connected at each end thereof to said vent jambs, said vent jamb including a flange extending therefrom adapted to overlie and close against a frame jamb, a baffle secured to said vent head and having an end thereof extending substantially to the inner face of its proximate frame jamb, means for securing said baffle to said vent head comprising complementary grooves and lands on said baffle and said vent head in snapping engagement, an operator secured to one of said vent jambs for moving the vent sash to open and closed positions including means on said operator for providing a pivotal connection to said frame jamb, and a baffle on said operator against stray light passing between the end of the first named baffle and its proximate frame jamb and between the end of said vent head and the proximate frame jamb, and complementary grooves and lands on said first named baffle and said operator baffle for additionally blocking light.

5. In an awning type window, a pair of spaced frame jambs, a frame head extending between said jambs including means for securing said jambs to said frame head, a vent sash adapted to pivot within the space defined by said spaced frame jambs and thereon to open and closed position, said sash comprising a pair of vent jambs and a vent head connected at each end thereof to said vent jambs, said vent jamb including a flange

extending therefrom adapted to overlie and close against a frame jamb, a baffle secured to said vent head and having an end thereof extending substantially to the inner face of its proximate frame jambs, means for securing said baffle to said vent head comprising complementary grooves and lands on said baffle and said vent head in snapping engagement, an operator secured to one of said vent jambs for moving the vent sash to open and closed positions including means on said operator for providing a pivotal connection to said frame jamb, and means on 10 said operator preventing stray light from passing between

the end of the first named baffle and its proximate frame jamb and between the end of said vent head and the proximate frame jamb, and complementary grooves and lands on said baffle and said last named means for additionally blocking stray light.
